(57) CLAIM

We claim the ornamental design for a brew basket, as shown and described.

DESCRIPTION

FIG. 1 is a perspective view of our brew basket according to an embodiment of the invention.

FIG. 2 is a first side view of a brew basket according to an embodiment of the invention.

FIG. 3 is a second side view of a brew basket according to an embodiment of the invention.

FIG. 4 is a top view of a brew basket according to an embodiment of the invention.

FIG. 5 is a bottom view of a brew basket according to an embodiment of the invention.

FIG. 6 is a first end view of a brew basket according to an embodiment of the invention; and,

FIG. 7 is a second end view of a brew basket according to an embodiment of the invention.

The broken lines in the drawings represent unclaimed subject matter and form no part of the claim.
